UNITED STATES PATENT OFFICE

123,759

DESIGN FOR A LAMP SHADE

Frederick J. S. Gay, Lahaina, Territory of Hawaii

Application July 15, 1940, Serial No. 93,679

Term of patent 14 years

To all whom it may concern:

Be it known that I, Frederick J. S. Gay, a citizen of the United States of America and residing at Lahaina, Maui, Territory of Hawaii, have invented a new, original, and ornamental Design for Lamp Shade, of which the following is a specification, reference being had to the accompanying drawing, forming part thereof wherein

I claim:

The ornamental design for a lamp shade, as shown.

FREDERICK J. S. GAY.
